[57] CLAIM

The ornamental design for a tray for storing merchandise, as shown and described.

DESCRIPTION

FIG. 1 is a top plan view of a tray for storing merchandise showing my new design, with the broken away portions indicating indeterminate length, and with it being understood that the aperture pattern would be continuous throughout;

FIG. 2 is a bottom plan view thereof;

FIG. 3 is a side elevation view thereof, the opposite side being a mirror image thereof; and,

FIG. 4 is an end elevational view thereof, the opposite end being a mirror image thereof.

The phantom lines indicate that the length and width of the tray for storing merchandise are indeterminate.
